(57) **CLAIM**

The ornamental design for a quick connection connector, substantially shown and described herein.

DESCRIPTION

FIG. 1 is a front, top and left side perspective view of a quick connection connector showing our new design;

FIG. 2 is a top plan view thereof;

FIG. 3 is a left side elevation view thereof;

FIG. 4 is a back side elevation view thereof;

FIG. 5 is a right side elevation view thereof;

FIG. 6 is a front elevation view thereof; and,

FIG. 7 is a bottom plan view thereof.

The broken line in the drawing views is included to illustrate the environment only and forms no part of the claimed design.
